ATTORNEY

UNITED STATES PATENT OFFICE.

MAX WALDECKER, OF ALBANY, NEW YORK.

PIANO FALL-BOARD.

SPECIFICATION forming part of Letters Patent No. 545,926, dated September 10, 1895.

Application filed May 16, 1895. Serial No. 549,527. (No model.)

To all whom it may concern:

Be it known that I, MAX WALDECKER, a citizen of the United States, residing at Albany, Albany county, New York, have invented 5 certain new and useful Improvements in Piano Fall-Boards; and I do hereby declare the following to be a full, clear, and exact description of the invention, such as will enable others skilled in the art to which it appertains 10 to make and use the same, reference being had to the accompanying drawings, and to the figures of reference marked thereon, which form a part of this specification.

The object of my invention is to provide a 15 new and improved fall-board for pianos.

In the drawings, Figure 1 shows a vertical sectional view of a part of an upright piano and my fall-board in the position it assumes when closed, and Fig. 2 a similar view showing 20 my fall-board opened with the music-rack thrown forward by the act of raising or opening the fall-board.

The numeral 1 shows the framework of the upper part of the piano; 2, the rear and 25 3 the front fall-board, hinged together and swinging on a pivoted arm 4, said arm 4 being attached to the front portion of the fall-board 3 in any well-known manner, but preferably by screws, the arm 4 being pivoted to the key-block 9, and being also provided with a lateral shoulder or offset, as shown in both figures, which extends past the hinge and supports and braces the contiguous parts of both fall-boards in their normal position. The detachable fastening of arm 4 to fall-board 3 30 permits the fall-boards to be very readily removed and put in place. Attached to and depending from the rear part of the fall-board 2 is a bracket 8, having a wheel or roller at its 40 lower end resting on a block which preferably slants rearward, the bracket 8 being preferably screwed to the fall-board 2 by a screw at its end, as shown in Fig. 1.

6 shows the music-rack pivoted or hung so it 45 will swing, as at 7, and behind the music-rack 6 is an arm 5, pivoted so it will also swing and strike the rack 6 and push it forward, the arm 5 being preferably a curved piece of wood; but it may be made of any material desired.

50 The operation is as follows: When the piano is closed the fall-boards lie in the position shown in Fig. 1. When the fall-board 3 is

raised or swung upward the effort so to do causes the fall-board 2 to be pushed back and tipped, as seen in Fig. 2, and as the fall-board 2 is not attached to the other part of the piano, but is left free to move rearward by means of the bracket 8 and its wheel, it has great freedom of action and cannot stick or jam fast, as fall-boards many times do that are attached 60 to the piano by hinges, swinging arms, and slotted connecting-pieces, as the wheel being pivoted to the bracket and the bracket free to assume any angle to the wheel and the rear fall-board 2 being free to move in space un- 65 restricted, except by the wheel and bracket which acts simply as a support therefor, there is never any hitching, faltering, or jamming fast of rear fall-board 2. As the fall-board 2 recedes it strikes against the lower end of 70 arm 5, pushing it rearward, while the upper end pushes against the rack 6, throwing it into the position shown in Fig. 2. As the fall-boards are returned to a closed position the weight of the rack 6 pushes the arm 5 back 75 to its normal position, the rear fall-board is drawn forward on the wheel at the end of bracket 8 without hinderance or liability to hitching, and in this manner I have produced fall-boards that will stand the roughest usage 80 and always move freely and without undue friction, and always assume the position designed for them when closed, the rear fall-board being left to assume any position it may, within certain limits, when it is pushed 85 rearward on opening the piano.

It will be seen that rear fall-board 2 is not in any manner connected to the piano or its frame, but is perfectly free to move except as the movement is controlled by the bracket 90 and wheel 8, and one of the main reasons why this is so arranged is that when boards 2 and 3 are set in place, the only attachment to be made is inserting the pivot on which arm 4 swings, and when it is desired to remove the 95 fall-boards the pivot is removed, when the boards are removed without further trouble and without being obliged to unhinge or otherwise disengage the rear board 2 from any fastenings whatever, and when they are put 100 in place, as board 2 is not dependent on hinges, pins, and like devices, it goes into place without loss of time or making trouble, which is a great advantage where numbers of

pianos are set up each day, as in the factory as it saves the time of the men whose business it is to assemble the parts of the piano, and this saving of time and trouble is a matter of 5 great importance to the manufacturer.

Having described my invention, what I claim is—

In combination with the rear and front fall-boards 2 and 3, hinged together as shown, and 10 the frame of the instrument, an arm 4 pivoted at its lower end to the said frame rigidly but detachably fastened at and near its upper end to the said front fall-board, overlapping

the joint of the said fall-boards and provided with a lateral offset to brace them on each 15 side of the same, the rear fall board being provided with a downwardly extending arm or bar having a wheel mounted thereon, for running back over the piano frame or casing substantially as set forth. 20

In testimony whereof I affix my signature in presence of two witnesses.

MAX WALDECKER.
